UNITED STATES PATENT OFFICE.

JOHN W. PAGE, OF CHICAGO, ILLINOIS.

EXCAVATING-SHOVEL.

1,379,311.

Specification of Letters Patent. Patented May 24, 1921.

Application filed March 17, 1919. Serial No. 283,030.

To all whom it may concern:

Be it known that I, JOHN W. PAGE, a citizen of the United States, residing at 1326 Fargo avenue, Chicago, in the county 5 of Cook and State of Illinois, have invented a new and useful Improvement in Excavating-Shovels, of which the following is a specification.

My invention relates to certain new and 10 useful improvements in excavating shovels and is fully described and explained in the specification and shown in the accompanying drawings, in which—

Figure 1 is a side elevation of the portions 15 of the bucket equipment in which my invention inheres. Fig. 2 is a vertical central longitudinal section on the line 2 of Fig. 3. Fig. 3 is a plan and Fig. 4 is a transverse section on the line 4 of Fig. 2.

20 The present invention consists in a device for firmly and satisfactorily securing together the loading or hauling line, its two horizontal extensions which run to the side of the bucket, and the upwardly extending 25 holding ropes which are employed in connection with the Page bucket which is now thoroughly known to and in common use among engineers. In the drawings, 5 is the hauling line, 6 are two chains forming 30 its horizontal continuations and which are attached to the two vertical side walls of the bucket at their front edge, and 7 is the holding line which runs diagonally upward around a sheave and down to a point on 35 the bucket in front of its center of gravity. It is of the utmost importance in the practical use of excavating buckets of this character, that these four lines be very securely attached together by means which the tremendous strains of use not only are unlikely 40 to destroy, but which are but slightly affected by wear. To this end, I provide a casting having at its forward end a forwardly tapered hollow tubular member 8,

45 which is considerably narrower horizontally than vertically. The hauling line 5 enters this member, is recurved upon itself around a grooved wedge-shaped piece 9 and is then drawn into the tubular member 8 from the 50 rear. In this way a wedging, self-binding connection is made between the loading line and the casting. Two arms 10 extend backward and outward from the tubular member 8 of the casting, the same being provided, as illustrated with suitable horizontal

and vertical ribs for strength. Each arm is forked at the rear forming furcations 14 and 15. 16 is a holding line casting, the same having a perforate bearing member 17 at its forward end and a vertical wedge-shaped tubular member 18 at its rear end, similar in general form to the tubular member 8. 19 is a shaft which extends through the furcations 14 and 15. The forward links in the chains 6 surround this shaft 60 and lie between the pair of furcations 14 and 15 on the two sides. The bearing member 17 of the holding line casting 16 likewise surrounds the shaft and lies between the two furcations 15. The shaft is held 65 in place by cross pins 20 engaging notches in the furcations 14. The holding line 7 is recurved upon itself to receive a wedge-shaped member 21, grooved to receive it and is drawn into the wedge-shaped tubular 75 member 18 on the holding line casting 16. This likewise forms a self locking and very tight connection.

The foregoing construction is very simple in construction and very rugged in operation. The various connections can be very quickly disengaged and reengaged if it is desired either to change ropes or to adjust the point at which one or another of the ropes is secured. The wedges which hold 80 the hauling and holding lines can be quickly knocked out when the ropes are slack and the cables can be readily readjusted. The holding line often is readjusted in practice, depending upon whether it runs directly 85 down to the shovel, or runs over a sheave and returns to adjust the amount of vertical lift which the bucket receives. It is to be noted that the bearing of the holding line casting on the shaft 20 is slightly eccentric so that a very considerable amount 90 of wear can take place before replacement is necessary.

I realize that considerable variation is possible in the details of the construction 100 herein shown, and I do not intend to limit myself thereto, except as pointed out in the following claims, in which it is my intention to claim all the novelty inherent in the device as broadly as is permitted by the 105 state of the art.

What I claim as new and desire to secure by Letters Patent, is—

1. In combination, a casting comprising a body portion having a wedge shaped tubular 110

opening therethrough, a pair of arms extending from said body portion, each of said arms being bifurcated at its outer end, a hauling line bent upon itself and passing through said tubular opening, a wedge co-operating with said tubular opening to hold the hauling line therein, a holding line, means for retaining said holding line and means carried by the arms to support said holding line retaining means.

2. In combination, a casting comprising a body portion having hauling line attaching means therein, a pair of arms extending rearwardly from the body portion, a bifurcated end on each of said arms, a second casting comprising a body portion having holding line attaching means therein, a member extending from said second mentioned body portion and terminating in a bearing member, and means carried by said arms engaging said bearing member to confine the same between the bifurcated ends.

3. In combination, a casting comprising a body portion having a wedge shaped tubular opening therethrough, a hauling line bent upon itself and passing through said tubular opening, a wedge co-operating with said opening to hold the hauling line therein, a pair of arms extending from the body portion and terminating in a bifurcated end, a second casting comprising a body portion having a wedge shaped tubular opening therethrough, a holding line bent upon itself and passing through said opening, a wedge co-operating with said opening to hold the holding line therein, a recessed member extending from said second mentioned body portion and terminating in a bearing member, a cross shaft carried by the bifurcations on the arms and forming a pivot for said

bearing member, and means for holding the cross shaft in position.

4. In combination, a main casting and a holding line casting, the main casting having two arms each bifurcated at the rear ends thereof, bifurcated ends carrying a cross shaft upon which the front of the holding line casting is pivotally supported between the central pair of bifurcations, horizontal extensions for the hauling line engaging the cross shaft between the members of each bifurcated end, wedge-shaped tubular members at the opposite ends of the two castings in which the hauling and holding lines are respectively held, each of said lines being recurved upon itself and passed through the wedge-shaped member and each having within its bight a grooved wedge whereby a self locking connection is secured.

5. In combination, a main casting and a holding line casting, the main casting having two arms each bifurcated at the rear, said furcations carrying a cross pin upon which the front of the holding line casting is supported between the central pair of furcations, horizontal extensions for the hauling line engaging the cross pins between the lateral pair of furcations, wedge-shaped tubular members at the opposite ends of the two castings in which the hauling and holding lines are respectively held, each being recurved upon itself and passed through the wedge-shaped member and each having within its bight a grooved wedge whereby a self locking connection is secured.

In testimony whereof I have hereunto set my hand and seal this 14th day of March, 1919.

JOHN W. PAGE. [L. S.]
